CLAIM

The ornamental design for a controller for a game machine, as shown and described.

DESCRIPTION

FIG. 1 is a perspective view of a controller for a game machine showing my new design.

FIG. 2 is a top view thereof.

FIG. 3 is a bottom view thereof.

FIG. 4 is a left side view thereof.

FIG. 5 is a right side view thereof.

FIG. 6 is a front view thereof; and,

FIG. 7 is a rear view thereof.

The electrical conduits show undermined length.
